UNITED STATES PATENT OFFICE.

FRANK HOWEY, OF VALLEY CITY, NORTH DAKOTA.

ADVERTISING-ENVELOP.

SPECIFICATION forming part of Letters Patent No. 745,187, dated November 24, 1903.

Application filed February 20, 1903. Serial No. 144,306. (No model.)

To all whom it may concern:

Be it known that I, FRANK HOWEY, a citizen of the United States, residing at Valley City, in the county of Barnes and State of North Dakota, have invented certain new and useful Improvements in Advertising-Envelops, of which the following is a specification.

It is customary in hotels, boarding-houses, stations, and business-places to supply patrons with stationery. This invention aims to utilize this practice as a means for distributing advertising matter, thereby giving a certain cast or individuality to the advertising matter as to render it reasonably certain of perusal by the recipient of a note or communication inclosed in an envelop embodying the invention.

This invention contemplates an envelop which to the casual observer is of ordinary appearance and construction, but which has an inner flap to extend over the advertising matter to protect, conceal, and prevent the easy removal of the same by the user and which will not interfere in the least with the accustomed use of the envelop. The recipient of a communication inclosed in an envelop embodying the invention removes the advertising matter simultaneously with the communication or other contents and is tempted to inspect the same as having a bearing upon the other contents, thereby bringing favorably to attention the matter to be published.

The invention consists of an envelop having in addition to the sealing-flap an inner flap for concealing, protecting, and confining advertising matter, which may be a card, circular, booklet, or the like, the parts being disposed so that the person receiving a communication inclosed in the envelop will upon opening the envelop and removing the communication likewise withdraw the advertisement and inspect the same as a part of the communication.

The invention further consists of certain structural features, which hereinafter will be more fully set forth, claimed, and illustrated in the accompanying drawings, in which—

Figure 1 is a view of an envelop embodying the invention as seen from the rear side. Fig. 2 is a perspective view of the envelop, the sealing-flap being extended and an end portion being broken away to show the relative

position of the advertising matter, the inner flap, and a communication. Fig. 3 is a transverse section of an envelop filled and sealed. Fig. 4 is a perspective view showing the manner of removing the contents of the envelop after the same has been opened.

Corresponding and like parts are referred to in the following description and indicated in all the views of the drawings by the same reference characters.

The envelop illustrated is of ordinary appearance and construction, and comprises a sealing-flap 1 and an inner flap 2, the latter being attached to a portion of the envelop adjacent to the opening adapted to be closed by the sealing-flap 1. The inner flap 2 is of a length approximating that of the envelop and is of a width to confine the advertising matter 3, so as to conceal, protect, and prevent the easy removal thereof by the prospective user. The flap 2 is located between the front and the back of the envelop and confines the advertising matter 3, which may be a card, circular, pamphlet, or like medium. By having the outer edge of the inner flap 2 attached to the body of the envelop adjacent to the opening a communication or other matter may be readily inserted into the envelop or removed therefrom with the same facility as attendant upon the use of the common envelop devoid of the flap 2. After the communication 4 or other matter has been introduced into the envelop and the latter sealed by folding the flap 1 thereover and gumming it to the back in the accustomed way, as indicated in Figs. 2, 3, and 4, said communication is not likely to be withdrawn from the envelop without removing the advertising matter, the entire contents of the envelop being removed at one operation, as indicated most clearly in Fig. 4. An end portion of the envelop is separated from the body by a break-line, as indicated at 5, the same being preferably a line of perforations, and a notice, such as

“Open here,” is inscribed upon the envelop adjacent to said break-line to call attention to the manner devised for facilitating opening of the same, and after the end portion separated by the break-line has been removed the edges of the envelop are pressed together, as indicated in Fig. 4, and the thumb and fingers introduced into the open end of the envelop to

- withdraw the contents, thereby bringing to light the advertising matter, together with the communication, the recipient of the communication inspecting the advertisement as a matter of course because of the supposed importance attached thereto by reason of the manner of its coming to hand. To prevent the end of the inner flap 2 being caught by the thumb and fingers grasping the contents of the envelop the inner lower corner of the flap 2 is cut away, as shown at 6.
- While it is preferred to provide the break-line 5, this is not essential, as the envelop may be opened in the usual manner by tearing off either end portion or slitting the fold between the front and the sealing-flap. In either case the contents of the envelop, including the communication and the advertising matter, are adapted to be removed.
- The invention may be applied to any style or make of envelop, and the inner flap 2 may be provided in any advantageous way and may be of any length and width with reference to the envelop so long as it serves to protect, confine, and conceal the advertising matter and prevent its displacement preliminary

to sealing the envelop after a communication or other matter has been placed therein.

Having thus described the invention, what is claimed as new is—

An envelop for distributing advertising matter, the same having an end portion separated from the body portion by means of a break-line, and an inner flap disposed within the body of the envelop and extending proximate the break-line of the end portion aforesaid for confining and protecting the advertising matter, and attached at its outer edge to a portion of the envelop adjacent to the opening and having the inner lower corner adjacent to the end of the break-line, cut away to facilitate grasping the advertising matter and other contents of the envelop after the end of the envelop has been removed.

In testimony whereof I affix my signature in presence of two witnesses.

FRANK HOWEY. [L. S.]
